No. 759,681.

Patented May 10, 1904.

UNITED STATES PATENT OFFICE.

JOHN N. QUINN, OF CINCINNATI, OHIO.

DEVICE FOR SHARPENING SHEARS.

SPECIFICATION forming part of Letters Patent No. 759,681, dated May 10, 1904.

Application filed February 15, 1904. Serial No. 193,528. (No model.)

To all whom it may concern:

Be it known that I, JOHN N. QUINN, a citizen of the United States, residing at Cincinnati, in the county of Hamilton and State of Ohio, 5 have invented certain new and useful Improvements in Devices for Sharpening Shears, of which the following is a specification.

My invention relates to an improvement in a device for sharpening shears by hand.

10 The features of my invention are more fully set forth in the description of the accompanying drawings, forming a part of this specification, in which—

Figure 1 is a side elevation of my improvement, showing a section of shear-blade in position and a stone in dotted lines. Fig. 2 is a front elevation. Fig. 3 is a top plan view.

15 A represents a flat table provided with an angular groove B for the reception of the shear-blade C. The angle of the groove relative to the table is such that when the shear-blade is in place in the groove the bevel *a* forming the cutting edge of the blade will be in horizontal plane with the table.

20 D represents a bracket-arm.

E represents a clamping-screw in the bracket-arm.

The under surface of the table and the end

of the screw *b* form a clamping-jaw which permits the device to be conveniently clamped 30 to a working bench.

F represents the sharpening-stone. (Shown in dotted lines.)

The blade is reciprocated lengthwise of its slot, and the flat stone is transversely reciprocated on a flat table.

This makes a very convenient sharpening device for artisans using shears in their daily work.

Having described my invention, I claim— 40

A device for holding shears when sharpening, consisting of a flat table having an angular groove formed therein, adapted to present the bevel edge of the contained shear-blade in the place of the flat table, a bracket-arm and 45 a clamping-screw therein, the under side of the table and the end of the screw constituting the clamping-jaws adapted to fit a bench or table, substantially as described.

In testimony whereof I have hereunto set 50 my hand.

JOHN N. QUINN.
